ADDING MACHINE SPOOL

Walter D. Landgraf, 4608 W. 96th Place, Oak Lawn, Ill.
Filed July 10, 1963, Ser. No. 294,093
2 Claims. (Cl. 197—175)

The present invention relates generally to spools, and more particularly to non-collapsible plastic spools for adding machine ribbons.

In accordance with the prior art ribbons for typewriters and adding machines have been wound on metal split rings. The split in the ring is essential to enable a reversing mechanism to sense that the spool has been exhausted of ribbon. Because the spool is split it collapses if the tension on the ribbon winding equipment varies slightly while a ribbon is being wound on a spool. In consequence, the spool will not fit the driving spindle of the machine in which it is to be installed.

In accordance with the present invention, a ribbon spool is fabricated of plastic, in one piece, generally a hollow cylinder. Provision for holding a ribbon end to the spool consists of a pair of parallel slots formed in the wall of the cylinder, extending halfway of its length in an axial direction, and spaced to leave a post for accepting a lengthwise slit in the ribbon located adjacent its ends.

A gap is provided for the reversing mechanism, which extends about 80% up, in a radial direction, leaving a bridge to complete the cylinder. From this bridge a tongue extends inwardly of the cylinder and fits a corresponding slot in driving spindle, acting as a driving or coupling element for the spool.

Provision of a bridge and tongue (1) prevents collapse of the spool, regardless of tape tension during winding, (2) provides a positive drive for the spool, (3) prevents the spool being installed upside down or otherwise incorrectly.

It is, accordingly, a broad object of the invention to provide a novel spool for an adding machine ribbon.

It is another object of the invention to provide a spool for an adding machine ribbon which includes a gap for accepting a reversing mechanism lever, bridged at one end to provide strength and rigidity, and also preventing incorrect installation of the spool and having an inwardly directed tongue associated with the gap to assure positive coupling with the driving spindle of the machine.

The above and still further objects, features and advantages of the present invention will become apparent upon consideration of the following detailed description of one specific embodiment thereof, especially when taken in conjunction with the accompanying drawings, wherein:

FIGURE 1 is a view in perspective of the conventional adding machine spool mount and reversing mechanism;

FIGURE 2 is a view in perspective of a spool according to the invention;

FIGURE 3 is a view in perspective of a spool and spool mount;

FIGURE 4 is a view in top plan of the structure of FIGURE 3;

FIGURE 5 is a view in section taken on line 55 of FIGURE 4;

FIGURE 6 is a view in bottom plan of the structure of FIGURE 3; and

FIGURE 7 is a view of the spool mount of FIGURE 3 in side elevation, taken with spool removed.

Referring now to the drawings, FIGURE 1 illustrates a driving and reversing mechanism for an R. C. Allen adding machine. A bottom flange 10 is provided with a central key slotted opening 11, for driving the flange by means of a keyed pin extending therethrough (not shown). Surrounding the opening 11 is an upstanding

2

hollow cylindrical mount 12 for a spool, the mount having an axial slot 13 to permit ingress of a sensing lever 14. The latter extends up through a slot 15, sufficiently long to enable the lever 14 to assume positions interiorly or exteriorly of the mount 12. The lever 14 is integral with an element 16, pivotally secured by a rivet 17 to the flange 10, and spring biased by a spring 18 to a position outside of mount 12. In normal operation the lever 14 is forced inwardly of mount 12, and the ribbon spool 19 is then slipped over the mount 12. The usual spool contains a gap through which the lever 14, biased outwardly by spring 18, senses presence or absence of ribbon on the spool. When absence is sensed the lever 14 is pulled through slot 13 by spring 14, and operates a ribbon reverse mechanism.

My novel spool is illustrated in FIGURE 2, wherein is displayed a cylindrical plastic structure 20, having a slightly larger inner diameter than the outer diameter of mount 12, so that it can be slipped thereon. The cylindrical spool 20 includes a gap 21, extending axially from the bottom edge 22 of cylindrical spool 20, to a point near its top edge 23, at which point the gap 21 terminates and a bridge 25 replaces same. Thereby at least a portion of the circumference of cylinder 20 is solid and rigid, so that cylinder 20 cannot collapse due to excess ribbon tension. A tongue 26 extends inwardly of bridge 25, and is just wide enough to mate with slot 13. The tongue 26 thus provides a positive drive or coupling for the spool 20. The tongue 26 is so located that the lever 14 can clear same, when installation is correct. If the spool is installed upside down the lever cannot operate.

At a position opposite to the tongue 26 are located two slots 30, 31, which are separated by a pin 32 of solid material. The slots extend about one half the height of the spool 20, from the top edge 23. A slit is cut near the end of the ribbon 35, which extends over the pin 32, the latter then serving as an anchor for the ribbon 35.

In operation, the slot 34 in ribbon 35 is placed over pin 32 and the ribbon 35 wound on spool 20, as in FIGURE 3. The lever 14 is then pressed inwardly of mount 12 and the wound spool mounted. Spring 18 then presses against the ribbon 35, through slot 13, and when the ribbon is entirely unwound can emerge into the position illustrated in FIGURE 3, to effect ribbon feed reversal.

While I have described and illustrated one specific embodiment of my invention, it will be clear that variations of the details of construction which are specifically illustrated may be resorted to without departing from the true spirit and scope of the invention as defined in the appended claims.

What I claim is:

1. A ribbon spool for installation on a rotary cylindrical drive spindle having a flange surface extending from the base and normal to the axis thereof, and having associated therewith a reversing lever pivotally attached to the underside of said flange surface, said lever including an upstanding pin extending through a cutout in said flange surface, said pivotal attachment and said cutout permitting movements of said pin substantially radially of said axis between a biased position exteriorly of said spindle and a ribbon sensing position interiorly of said spindle through an associated gap therein, said spool comprising a hollow cylinder arranged to mate with said spindle and to seat against said flange surface, a slot extending through the wall of said cylinder from the seat end thereof to a point adjacent the other end thereof, a tongue portion projecting inwardly of said cylinder along the terminus of said slot and substantially coextensive with the width of said gap, said tongue portion

arranged to mate with said gap to align said slot therewith and to couple said spool to said spindle for rotation therewith, said slot having a length sufficient to permit said pin to travel freely therethrough in the absence of ribbon on said spool, said tongue portion projecting inwardly of said spindle beyond the point of maximum inward travel of said pin when said spool is seated on said spindle, so that said pin and tongue portion interfere to prevent seating of said spool against said flange surface in the event of improper installation of said spool.

2. The combination according to claim 1, wherein a

pair of parallel longitudinal slits is provided through said wall of said cylinder extending from said other end toward said seat end, said slits defining an anchor pin therebetween for securing said ribbon to said spool.
